FIG. 1 is a perspective view of a bottle carrier according to my new design, shown with the closure and handle in broken line representation and forming no part of the design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top plan view of an alternate embodiment of a bottle carrier shown in an opened condition, whose views in the closed condition are those shown in FIGS. 1-7;

FIG. 9 is a side view of the bottle carrier of FIG. 8 in the opened position; and,

FIG. 10 is an opposite side view of the bottle carrier of FIG. 8 in the opened position.

The broken lines showing the handle, the closure and interior of the carrier are for the purposes of illustrating environment and form no part of the claimed design.
